[57] CLAIM

The ornamental design for a combined jar and lid, as
shown and described.

DESCRIPTION

FIG. 1 is a top, front perspective view of a combined jar
and lid showing our new design;

FIG. 2 is a front elevation thereof, the rear elevation is
the same;

FIG. 3 is a side elevation thereof, the opposite side is the
same;

FIG. 4 is a top plan view thereof;

FIG. 5 is a bottom plan view thereof; and

FIG. 6 is a cross sectional view taken along line 6—6 in
FIG. 1.
